UNITED STATES PATENT OFFICE.

FRANK B. COMINS, OF NEWTON, MASSACHUSETTS, ASSIGNOR TO AMERICAN MOISTEN-
ING COMPANY, OF BOSTON, MASSACHUSETTS, A CORPORATION OF MAINE

CENTRIFUGAL HUMIDIFIER.

Application filed August 10, 1922. Serial No. 580,887.

This invention relates to improvements in centrifugal humidifiers. More particularly it relates to apparatus in which water is thrown by centrifugal action, and thus broken into fine particles by mechanical power, and is then carried away vaporized in a current of air generated by a near-by fan. The breaking up into fine particles of liquid which may float in air is herein called atomizing, and the converting of such into vapor, invisible in the air, is called vaporizing. These terms are here thus defined because they are sometimes used in the trade with somewhat different meanings.

In apparatus heretofore proposed, a rotating disk throws water centrifugally against an arrangement of obstructing blades by which the flying film of liquid is finely subdivided, the disk and fan being operated by a small electric motor. The present invention provides improvements in such apparatus.

It is an aim of the invention to provide for a very full loading of vaporized water on the passing current of air. Another object is to provide for complete and harmless drainage of whatever excess of water remains above that which is thus transferred to air, when the apparatus is in operation; also to provide for safe drainage in case the water supply is left flowing when the rotation is stopped. A feature which tends toward a realization of the first of these aims is the formation of the blades or teeth, by which water is atomized, in the form of two long curls or helices of metallic ribbon commonly called spirals. These may preferably be stationary at the periphery of the rotating disk, each extending semi-circularly from its top to its bottom. They afford a relatively great length of edge and a large surface exposure of water to air, under circumstances where air and water are in relative motion, and where the tendency for atomizing and also for evaporation are strongest; and they afford a drain for any water that is not carried off floating in the air, or as vapor, to run down to the bottom without diminishing the said great edge length and exposure surface. Co-operating with these is a rotor which is a combined tubular and plane water spreader and air fan.

Other features of the invention are to

adapt the principal parts by which the above 55 named general aims are accomplished so that they perform their respective functions with a high degree of efficiency, and in general to provide the other advantages which characterize the invention disclosed. 60

In the specific embodiment of the invention here illustrated the blades of a fan constitute flat tubes for conveying water from the hub outward to an annular plane rim at their extremities, from which it flies 65 against a peripheral helix of metallic ribbon whose convolutions are suggestive of cones and whose "axis" is a semi-circular curve paralleling the periphery of the rotating rim. This ribbon, whose surface is 70 more or less covered with water, in the aggregate presents a dimension of metallic edge very largely multiplied as compared with the circumferential dimension of the disk. Owing to smallness of radius of curvature of the metal at the said edge, the water has but a weak hold upon it, and the water has high relative motion with respect to the air which passes transversely and longitudinally through the conical elements of 80 the helix, thus causing a high state of humidifying. Whatever water does not pass off with the air runs down the wall of the conical element whereon it is, outside or inside, to the midst of the helix, and then 85 drops from cone to cone interiorly of the helix, to the bottom of the casing, whence it drains away. It will be understood that variations may be made from the particular form that is here shown for illustration. It 90 is intended that the patent shall cover, by suitable expression in the appended claims, whatever features of patentable novelty exist in the invention disclosed, except that the conical helix for atomizing, vaporizing and 95 drainage, is the subject of a separate application for patent.

In the drawings:

Figure 1 is a perspective of apparatus embodying the invention, with a fragment 100 broken away to disclose the interior.

Figure 2 is a side elevation in medial section through the apparatus of Figure 1, omitting the motor and showing a modified form of spiral deflector which is part of the 105 rotor;

Figure 3 is an end elevation, in section on the line 3—3 of Fig. 2; but showing a spiral

deflector like that of Figure 1 which is not a part of the rotor.

Figure 4 is a section on line 4—4 of Fig. 3, showing a detail, enlarged;

5 Figure 5 is a section on the line 5—5 of Fig. 3, showing details as seen from that line looking in the direction of the arrows.

Figures 6, 7 and 8 are sections showing 10 details respectively on the lines 6—6, 7—7 and 8—8 of Fig. 3 looking in the direction of the arrows at the ends of each of the said lines.

15 Figure 9 is an elevation of a fragment, in section as indicated at 9—9 in Figure 2, showing attachment of the spiral deflector to the rotor;

20 Figure 10 is an elevation of a fragment of the apparatus shown in Figures 1 and 3, representing the arrangement at the place 25 corresponding to the upper part of Figure 2; and

Figure 11 is an elevation, in section on line 11—11, of the fragment which is seen in Figure 10.

25 In the drawings, 10 indicates a source of power, which, as represented, is an electric motor, for rotating the shaft 11 on which is mounted a rotor whose form is best seen in Figure 1, within the fixed casing or hood 30 12. This hood is about the periphery of the rotating part, whose principal elements are the hub 13, the tubular fan blades 14 and the peripheral plane 15. In the form illustrated in Figures 1, 3, 10 and 11, the conical 35 spiral deflector is in two sections 16 and 16' each stationarily mounted within the hood 12 close outside of the edge of the disk. The sections are semi-circular, each having its cones pointing downward. The rotary 40 disk 15 is a simple plane ring at the extremities of the arms 14. The arms 14 are tubular, of the peculiar cross section seen in Figure 4, each tube being thin at its leading edge and thick at its lagging edge in order 45 both to provide externally a sharp edge for cutting the air and internally an ample space for flow of water along that wall of the tube to which the water is thrown by inertia as the water moves outward on the rotating element. These blades are spirally 50 arranged, so that water which starts in the tube of a blade can lag therein without piling up too much on the rear wall of that tube as it progresses from hub to periphery; and these blades are set askew, as is 55 seen in Figure 5 in the way which is common with fan blades, so that the leading face of the fan blade propels air as the blade proceeds in its rotation. As the extremity of each blade is in a plane, where 60 it makes junction with the plane annular surface at the periphery, it follows that the metal of the blade is bent askew rather sharply just adjacent to the said peripheral plane, as indicated in Figure 5 and in Fig-

ures 6, 7 and 8, in each of which latter figures the open delivery end of the tubular blade is seen. In Figure 7 a portion is represented which is at the middle of the end of the blade and is therefore in the plane of the ring 15, but in Figure 6 a portion is seen at the leading edge of the fan blade, where the blade is set back from the plane; in Figure 8 a portion is seen near the lagging edge of the blade which is set forward out of said plane; and in all of these cases the open escape for water is seen. The atomizing edge 16 is a helix of metallic ribbon whose axis curves around circularly so that the helix goes around the periphery of the rotating plane 15. In the form illustrated in Figs. 1, 3, 10 and 11 this helix may be mounted by being secured at intervals to said hood. The helix 16 or 16', or 16^a of the form shown in Figures 2 and 9, consists of 70 flat metallic ribbon, each convolution thereof being roughly a section of a hollow thin walled cone. The convolutions may be of any desired pitch. I have found it preferable to make them fairly close together, yet 75 with ample spaces for passage of air in through the openings between them to the relatively large hollow center of the helix. If the diameter of the helix be, for example, 80 one-half inch and there be eight convolutions to an inch, it follows that in each inch of circumference of the disk there will be about 13 inches of length of metallic ribbon; and as this has two edges and two faces 85 there are in said inch of periphery a total 90 of some 26 inches of edge and also 26 inches in length of ribbon surface available for carrying water and dispensing it to the passing air. The stationary rim 12 is suitably mounted as by a bracket 20 and is 95 shaped, as seen in Figure 2, so as to provide 100 a passage for air around the periphery of the rotor. To this end the casing or hood has a part which extends somewhat inward from the periphery on the side from which 105 air approaches, as at 12' in Figure 2, while 110 its edge on the side toward which air departs is more nearly opposite the periphery of the rotating member as seen at 12'' in Figure 2. The curvature around the periphery 115 serves both to direct air which flows there and to collect any water which may be thrown out by centrifugal force in globules too large to be carried off by the air 120 and which may fail of being drained by the helix, or any water which drains from the blades when they are stationary or rotating at low speed. The inlet for water is the pipe 22, best seen in Figure 2, which discharges into the hollow hub in a direction 125 toward the periphery.

In operation, water running from the pipe 22, or projected therefrom with force if desired, is continuously delivered toward the periphery of the rotor and passes into the 130

tubular fan blades, one after another as they go by the incoming stream. The water which thus enters one of those rotating blades, moving toward its periphery, is pulled along in the direction of rotation by friction of the moving metal, is held back by its own inertia, and is moved outward by centrifugal force, so that it becomes gradually spread out over the front and back side 5 walls of the tubular blade; and any which lags sufficiently is picked up by the edge of the tube which is behind in the rotation. The increasing speed of the walls on which the water is carried, as the water gets further 10 away from the center, continues the tendency of the water to spread over the surface; and in the end the water is disseminated in a thin film which flows at will under the influences above mentioned over the plane portion 15 of the rotor to the edge thereof where it is thrown off against the atomizing helical conical ribbon. If this ribbon be a part of the rotor as in Figures 2 and 9 the water can pass thereto without violent shock and 20 is then further distributed and exposed to air, for evaporation or for being broken up into small particles, called atomizing. The current of air which is propelled in the axial direction through the central part of the apparatus, by the said fan blades, draws air also through the peripheral portion of the apparatus. The helix of ribbon at the periphery causes a great commotion in the air which is there; and there may be, if desired, 25 stationary blades so that the air moving around with it under its propulsion is deflected in the forward direction, thus augmenting the flow of air past the periphery. Such particles of liquid as are carried away 30 from the periphery find air for their prompt evaporation in the body of air which is rushing through the center of the rotor, impelled by the fan blades there located; so that the product of the apparatus is a stream 35 of humidified air, the production of which has been accomplished without the need of a supply of air under high pressure or of water under high pressure, and with the requirements only of an ordinary supply of 40 water and a very moderate electric current such as can operate a small fan.

The disclosed structure provides for atomizing liquid and also for vaporizing it. The helically formed ribbon serves as 45 atomizing means for liquid impacted against it, and further atomization is effected by impact of water against the casing or hood. The structure and assemblage of parts whereby a large amount of wet surface is 50 presented in the path of the air results in vaporization of liquid. A relatively large evaporating surface is provided by having a spirally formed ribbon, and the hood 12 is continually wetted by flying water so that 55 it presents a large evaporating surface over

which air directed outward by the fan passes before escaping into the room atmosphere. Thus a considerable amount of vaporization is effected, over and above that which naturally occurs in the atomizing region. 70

With the form shown in Figures 2 and 9 the individual spirals of the helix, which are in the nature of cones should be arranged to move with their small ends in advance. This causes the water to tend to pass over 75 the outsides of the successive conical spirals with pressure of rushing air upon it, as the cones drive forward, pushing the water over the surfaces and to the edges of the tape and from cone to cone with constant opportunity for it to be taken up by the air.

In the form shown in Figures 1, 3, 10 and 11 where the spiral deflectors are not a part of the rotor, the action is different. The water leaves the edge of the rotor and flying 85 through the air strikes the deflectors with violent shock which to an extent breaks it into small globules by impact and spattering. Such water as is not borne off initially by air is spread out over the conical surfaces 90 of the spiral deflectors, 16 or 16', whence more of it is taken by the air; and such as is not taken runs by gravity down the conical deflector-surfaces on which it is caught, and passes down the centre of the succession 95 of like surfaces, to drain out at the bottom without deepening the coats of water on the lower conical deflector-surfaces, thus leaving these surfaces in condition to continue to afford violent shock to the flying 100 film of water which is constantly arriving upon them from the edge of the rotor. By this arrangement the deflectors 16, 16' continually break up the film, collect such water as is not atomized or vaporized, remove it 105 from the surface that has received it, and drain it in a separate path where its flow is uninterrupted, for quick drainage, and where it does not interfere with the atomizing action. 110

Although the drawings show that form of the invention in which the blades are in the form of tubes it will be understood that in some cases one wall of the tube may be omitted and the water carried on the unenclosed surface of the blade, as it moves from the hub toward the peripheral ring. 115

What I claim is:

1. A centrifugal humidifier, comprising a 120 rotor with water-carrying fan blades adapted at their extremities to discharge water centrifugally; a water-carrying discal ring joining their extremities and adapted to spread the water into a film; and means for atomizing the water discharged centrifugally 125 from the ring.

2. A centrifugal humidifier, comprising a 130 rotor with tubular water-carrying fan blades; means whereby water is introduced to the interior of said blades at the hub; a

- discal ring at the periphery of the rotor carrying at its surface water discharged from said tubular blades and forming it into a film; and means for atomizing the water discharged centrifugally from said ring.
3. A centrifugal humidifier, comprising a rotor adapted to distribute water centrifugally into a film, combined with a succession of hollow substantially conical elements extending around the periphery of rotation said elements being open at their points and rotating with the rotor.
4. A centrifugal humidifier, comprising a rotor adapted to distribute water centrifugally into a film, combined with a metallic ribbon formed helically into convolutions which individually are conical and which extend as a series around the periphery of the rotor, at a small distance therefrom and rotate therewith.
5. A centrifugal humidifier, comprising a rotor with tubular blades, constituting externally a fan and internally a water-carrier, the said blades being made with triangular cross section, having an angle of the triangle in the lead and having a side of the triangle in the rear extending outward from the axis at an angle suitable for moving water centrifugally on it, whereon water lagging as it moves centrifugally may be carried around, there being at the peripheral edge of said blade an opening for escape of water in radial direction.
6. A centrifugal humidifier, comprising a rotor with tubular blades externally constituting fan blades and internally constituting water carriers, combined with a peripheral plane ring adapted to distribute into a film the water delivered by the blades; the leading face of each said blade being set at an oblique angle to the axis and extending to both sides of the plane of the ring.
7. A centrifugal humidifier, comprising a rotary fan having at its hub means to receive water and peripheral openings to deliver said water to the arms of the fan; said arms, comprising water distributing spiral blades; peripheral continuations of the blades for distributing the water centrifugally therefrom into a circular film; atomizing means at the edge of said continuations of the blades; and an annular hood guiding air past the said edge and providing drainage.
8. A centrifugal humidifier, comprising a rotary fan having at its hub means to receive water and peripheral openings to deliver said water to the arms of the fan; said arms, comprising tubular, water-distributing spiral blades; a peripheral plane ring to whose surface the tubes of the blades deliver; atomizing means at the edge of said ring; and an annular hood guiding air past the said edge and providing drainage.
9. A centrifugal humidifier, comprising a rotor with blades which constitute on one surface a fan and on another surface a water carrier, combined with a flat surfaced ring surrounding and joining them, whereto the water carried by them is delivered centrifugally; and vaporizing means at the edge of the ring comprising a series of substantially conical surfaces continually wetted by water discharged centrifugally by said ring.
10. A centrifugal humidifier comprising, a rotor with tubular water-carrying arms whose faces constitute fan blades, the hub ends of the tubular blades being open to atmosphere at the hub for admission of water and air to the interiors of the blades; a water supply pipe at the hub, the said admitted air being taken directly from atmosphere; the tubular interior of each said blade having a wide and thin outlet at its end for discharge of water centrifugally; and means closely adjacent, for atomizing the water thus discharged.
11. A centrifugal humidifier comprising, a rotor with water-carrying arms, with skew faces constituting propeller blades for air; each having means for receiving supply water at the hub and each having a flattened opening at its tip for centrifugal discharge of water as a film; adjacent circumscribing means for atomizing the water thus discharged; and means inducing vaporization of the atomized water, comprising a hood circumscribing the tips of the fan blades and said atomizing means, constituting a drainage trough for unatomized and unvaporized water with discharge at its bottom, and leaving an axial opening for flow of air substantially equaling in diameter the path of the fan blade tips.
12. A centrifugal humidifier comprising, a rotor with water-carrying arms with skew faces constituting propeller blades for air; each having means for receiving supply water at the hub and each having its tip end bent in direction to effect centrifugal discharge of water as a film; adjacent circumscribing means for atomizing the water thus discharged; and a closely circumscribing hood leaving an axial opening approximating the diameter of said circumscribing atomizing means.
13. A centrifugal humidifier comprising, a rotor with water-carrying arms with skew faces constituting propeller blades for air; each having means for receiving supply water at the hub and each having a flattened outlet at its tip for centrifugal discharge of water as a film; and each blade having its edge which lags, in direction of rotation, constituting a spiral element providing space on that blade, between this lagging edge and the leading edge, for water thereon to lag in angular motion with respect to the rotor as it proceeds thereon from entrance at the hub end of said lagging edge to said dis-

charge; and means circumscribing the tips of the blade for inducing atomization and vaporization of the discharged water.

14. A centrifugal humidifier comprising, a
5 rotor having tubular blades externally con-
stituting air propellers and internally con-
stituting water carriers; said blades having
a flattened outlet therefrom at the periphery
of the rotor whereby the water is discharged
10 as a film; and means adjacent the edge of
said rotor for atomizing the water thus dis-
charged.

15. A centrifugal humidifier comprising, a

rotor having air-propelling blades; means at
the axis of said rotor for supplying water 15
to said blades; the blades being curved from
the said axis to their tips so that the water
in its movement outward due to centrifugal
force is spread over said blades and dis-
charged from the end thereof as a film; and 20
means in the path of said film for atomizing
the water thus discharged.

Signed at Boston, Massachusetts, this
ninth day of August, 1922.

FRANK B. COMINS.
